MACHINE FOR CUTTING TOBACCO
AND THE LIKE

Patrick Quintin Robert Schreiber, London, England, assignor to Robert Legg Limited, London, England, a British company

Application March 22, 1950, Serial No. 151,071
In Great Britain March 24, 1949

8 Claims. (Cl. 146—119)

1

This invention relates to machines for cutting leaf tobacco.

In tobacco-cutting machines it is customary for the uncut tobacco to be fed to a mouthpiece by means such as two converging endless bands so that the tobacco is compressed as it passes through the mouthpiece. At the outlet side of the mouthpiece thin slices of the compressed tobacco are cut off. There are many advantages attaching to the use of rotary machines in which a cutter in the form of a drum rotates in front of the mouthpiece. Such a cutter can carry a plurality of knives, each as a general rule having its cutting edge substantially parallel to the axis of rotation, so that the machine cuts a plurality of slices of tobacco in each revolution and the output is therefore high. Now, as each knife is on the drum, a pocket must be provided in the drum to accommodate the slice of tobacco as it is cut by the knife. The tobacco is carried clear of the mouthpiece by the pockets and carried onwards in them during the continued rotation of the cutter. It then becomes necessary to remove the tobacco from each pocket, and the means used for this purpose hitherto are not altogether satisfactory.

It is an object of the present invention to provide means for positively ejecting cut tobacco from a pocket in a rotary cutter.

It is another object to provide mechanical means by which cut tobacco is pushed out of the pockets of a rotary tobacco cutter.

It is a further object to provide means for setting up streams of air to carry cut tobacco out of the pockets.

It is yet a further object to prevent pieces of cut tobacco from escaping into the atmosphere around the machine or hindering operation of the apparatus.

Further objects and advantages of the invention will appear from the following description of the preferred embodiment, in which reference is made to the accompanying drawings. In these drawings:

Figure 1 is a side elevation of the complete machine;

Figure 2 is a sectional elevation of part of the machine on a larger scale viewed from the other side;

Figure 3 is an end elevation of the machine in section on the line III—III in Figure 2;

Figure 4 is a view of part of Figure 2 on a still larger scale;

Figure 5 is a detail of Figure 4; and

Figure 6 is a perspective view of an ejector bar and associated mechanism.

The ejector bars and associated mechanism which appear in Figures 4 to 6 are for clarity omitted from Figures 2 and 3.

Broadly stated, I have discovered that the cut

2

tobacco can be ejected positively from each pocket by making the bottom of the pocket movable and actuating it by a cam or the equivalent in the course of the rotation of the cutter drum.

I have also discovered that the cut tobacco can be ejected by an air blast produced by suction.

I prefer to embody both my discoveries in the machine and to eject each slice mechanically while dislodging any small pieces of tobacco pneumatically.

In the apparatus shown in Figs. 1 and 2, tobacco is fed to a space 2 between two conveyors 4 and 6 by which it is carried to a mouthpiece 8 and is at the same time compressed. Opposite the mouthpiece there is a rotary cutter in the form of a hollow drum 12 having a plurality of knives 10 mounted around its circumference, each knife being arranged with its cutting edge substantially parallel to the axis of the drum. Each knife in turn sweeps across the outlet from the mouthpiece and cuts the tobacco which is protruding from the mouthpiece. In consequence, a succession of thin slices is cut, and each slice enters a pocket 16 formed in the drum 12 beneath the knife by which it is cut. The inner and outer walls 15 and 17 of each pocket are parts of the concentric cylinders, the outer wall 17 meeting the plane of the underside of the knife 10 at a small angle. This is best illustrated in Figs. 2, 4 and 5. Each slice of tobacco tends to disintegrate into shreds, and these shreds are urged centrifugally against the outer wall 17 and are retained in the pocket by friction against this wall until they are positively ejected after the drum 12 has rotated through about 90°.

The ejection is primarily effected by making the bottom or base of each pocket movable. For example, see Figs. 4, 5 and 6. Thus, the base of each pocket 16 consists of a bar 18, having its ends connected by links 20 to cranks 22 and 23 on each end of a shaft 24. Turning of this shaft causes the bar to move and eject tobacco from the pocket. Each crank 22 carries a roller 26 which is held in contact with a fixed cam 28 by a spring 30. This cam is mainly concentric with the drum 12, but is deformed at its lower part to cause downward ejection of tobacco after it has been cut.

It is possible to dispense with the springs 30 and provide a cam groove with which the rollers 26 engage.

The tobacco when ejected enters a hood 32, which encases the lower part of the cutter drum 12 as shown in Figs. 2 and 3. The hood merges into a duct 34 which leads to a settling chamber 36, Fig. 1, to which a fan 38 is connected. This fan maintains a partial vacuum within the hood 32 and so air tends to flow outwards through

the pockets into the hood. To permit this flow each bar 18 is made narrower than the distance between walls 15 and 17, and since it is free to swing on the links 20, the bar moves centrifugally across the pocket into contact with the wall 17, so leaving a clearance 35 between it and the inner wall. This is illustrated in Figs. 4 and 5. Thus the bar scrapes the wall 17 during ejection and at the same time air can flow outwards through the pocket carrying with it any small particles of tobacco not ejected by the bar alone. Thus, the pocket is cleared of tobacco and particles are prevented from jamming between the bar and the walls of the pocket. Moreover, clearance 37 is deliberately left between the hood 15 and the surface of the drum 12, so that air flows inwards at this point. This ensures that tobacco does not escape into the atmosphere or remain adhering to the surface of the drum.

The part-circular shape of the pockets presents several advantages. It allows the mechanism for moving the ejector bar to take the simple form shown, whereas if the pockets were straight the mechanism would have to be more complicated. It is easier to connect the mouth 20 of the pocket to the inside of the drum by a part-circular pocket than by a straight pocket, bearing in mind that at the mouth the pocket must make only a small angle with the knife. Moreover, tobacco would tend to pass right 30 through a straight pocket into the interior of the drum.

In the hollow interior of the drum 12 there is a duct 39, see Figs. 2, 3 and 4, which communicates only with the pockets which are within 35 the hood 32. This prevents suction being set up within the remainder of the interior of the drum and drawing tobacco inwards through the pockets which are facing upwards. Air from the atmosphere enters the duct 39 at 40 through a hollow stub axle 42 of the drum 12.

Tobacco carried into the hood 32 falls into the duct 34 and is carried either by the air stream or by a conveyor 44 into the settling chamber 45. Here all the tobacco settles on a conveyor 46 by which it is carried away from the machine.

It is not necessary for the cutting edges of the knives 10 to be exactly parallel to the axis of the drum 12, and they may if desired lie, for example, on a helix. In the example shown, 50 the cutting edges are in fact on a very coarse helix so that the knives engage the tobacco progressively at each cut.

I claim:

1. In a tobacco cutting machine, in combination, a mouthpiece, means for feeding tobacco to said mouthpiece to protrude therefrom, hollow rotary cutting means adapted to cut said protruding tobacco into successive slices, walls in said cutting means defining a pocket adapted to receive a cut slice and communicating with the hollow interior of said cutting means, mechanical means including a member movable toward the mouth of said pocket to eject said cut slice when said pocket is clear of said mouthpiece, said member being of less width than said pocket and also movable freely transversely in said pocket to scrape against one wall thereof and leave a clearance from the opposite wall thereof, and means for applying suction to said mouth during movement of said member toward said mouth to cause air to flow through said clearance to assist ejection of said cut slice.

2. In a tobacco cutting machine, in combination, a mouthpiece, means for feeding tobacco

to said mouthpiece to protrude therefrom, a drum mounted to rotate in front of said mouthpiece and carrying knives which extend in the direction of the axis of said drum and are adapted to cut said protruding tobacco into successive slices, walls in said drum defining a pocket adapted to receive a cut slice and extending outwardly from the central portion of said drum and terminating beneath the cutting edge of each of said knives, and mechanical means including a member movable toward the mouth of said pocket to eject said cut slice when said pocket is clear of said mouthpiece, said member being also movable freely transversely to the ejecting movement in said pocket to scrape against the outer of said walls during movement toward said mouth and thereby dislodge any tobacco adhering to said walls and eject said dislodged tobacco with said cut slice.

3. An arrangement as set forth in claim 2, in which the walls of each pocket are surfaces of concentric cylinders.

4. An arrangement as set forth in claim 3, in which the outer wall of said pocket intersects the plane of the underside of said knife at a small angle.

5. An arrangement as set forth in claim 4, in which the angle is 10°.

6. An arrangement as set forth in claim 2, and rods bearing a crank at each end and links connecting said cranks to the ends of said member, whereby oscillation of said rod causes said member to move to and from the mouth of said pocket.

7. An arrangement as set forth in claim 6, a fixed cam and a roller on one crank of said rod, with said roller bearing on said cam.

8. In a tobacco cutting machine, in combination, a mouthpiece, means for feeding tobacco to said mouthpiece to protrude therefrom, a hollow drum mounted to rotate in front of said mouthpiece and carrying knives which extend in the direction of the axis of said drum and are adapted to cut said protruding tobacco into successive slices, walls in said drum defining a pocket extending from beneath the cutting edge of each of said knives to the hollow interior of said drum, a stationary hood surrounding an arc only of the exterior of said drum clear of said mouthpiece, means for maintaining a partial vacuum within said hood, and a stationary duct within said hollow interior adapted to connect those only of said pockets which are surrounded by said hood to atmosphere independently of the remainder of said pockets, whereby an air current is caused to flow outwards through the pockets surrounded by said hood while no current flows through the remainder.

60 PATRICK QUINTIN ROBERT SCHREIBER.
